UNITED STATES PATENT OFFICE.

CLINTON W. RIEFF, OF WEST FORK, ARKANSAS.

TOOL-HANDLE.

1,397,783.

Specification of Letters Patent. Patented Nov. 22, 1921.

Application filed September 1, 1920. Serial No. 407,390.

To all whom it may concern:

Be it known that I, CLINTON W. RIEFF, a citizen of the United States, residing at West Fork, in the county of Washington and 5 State of Arkansas, have invented certain new and useful Improvements in Tool-Handles, of which the following is a specification, reference being had to the accompanying drawings.

10 This invention relates to tool handles and particularly to a tool handle for wrenches.

An object of the invention is to provide a handle having a chamber in which an oil can is mounted, said oil can being concealed 15 within the handle when the tool is in use and capable of being extended laterally of the handle for the discharge of oil from the can.

Another object of the invention is to provide 20 a handle of this character which protects an oil can disposed therein at all times. Another object of the invention is to provide a handle of this character adapted to receive an oil can, the oil can being provided with a 25 collar which is freely mounted on a removable shaft, said shaft being readily disengaged from the handle to permit removal of the can.

With the above and other objects in view, 30 the invention consists in the improved construction and arrangement of parts to be hereinafter more particularly described, fully claimed and illustrated in the accompanying drawings, in which:—

35 Figure 1 is a view in side elevation of a tool handle constructed in accordance with an embodiment of my invention, with the oil can in a working position,

Fig. 2 is a fragmentary view partly in elevation and partly in section of the handle as 40 herein disclosed, and

Fig. 3 is a fragmentary view partly in side elevation and partly in section of the handle as herein embodied.

45 Referring to the drawings, 5 designates the shank of a wrench, said shank having the usual ratchet teeth 6. A slideable jaw 7 is mounted on the shank, said jaw being provided with a pawl 8, a spring 9 being secured 50 to the pawl at one end and engaged with the lower surface of the jaw at its opposite end.

55 My improved handle is particularly adapted for use in connection with a wrench such as described above, but it is obvious that it may be used in connection with any form of tool

using a handle. The handle consists of a hollow body member 10 open at its side 11 and ends 12 and 13. The end 13 is adapted to conform to the end of the shank of a tool, the shank being secured within the end. The 60 side 14 of the handle is provided with a slot 15 which is disposed adjacent the end 13, the purpose of which will be hereinafter described. Extending transversely of the handle, is a shaft 16 one end of said shaft being 65 reduced and adapted to extend through an opening 17 formed in the side portion 18 of the handle, the opposite end of the shaft being journaled in an opening 20 provided in the side portion 19 of the handle. The reduced portion of the shaft provides a shoulder which prevents the shaft from moving through the opening 17. The shaft is maintained in position within the handle by means of a spring plate 21, which is pivoted 70 to the side 19 adjacent the opening 20.

A collar 22 is adapted to surround the spout B of the can adjacent the body thereof, said collar having its ends extended in right angular relation and engaged with each 80 other, an opening 23 being provided in the ears. The can is intended to be disposed within the chamber formed in the handle, the shaft 16 being passed through the openings 23 to pivotally support the can within 85 the handle. When it is desired to discharge oil, the can is swung upon its pivot so as to permit the spout B to extend through the slot 15, while the body of the can extends through the openings 11. In view of this it 90 is only necessary for the operator to compress the end of the can in order to discharge the oil, as the can is supported at all times by the handle. Secured to the side 14 and extending over the end 12 is a spring clip 24 95 which is intended to engage the bottom of the oil can to retain the same within the handle when not in use.

An important feature of this novel form of handle, is that the can is disposed within and protected by the handle at all times and as it is firmly held therein by means of the clip 24, it does not interfere with the use of the tool. In addition to this, when it is necessary to supply the can with oil the spring plate 21 is moved to one side so as to permit removal of the shaft 16 whereupon the can may be readily disengaged from the handle and supplied with oil. This handle is especially adapted for use in connection with 100 105 110

wrenches so that oil may be applied to nuts without requiring the operator to lay the wrench down as the can may be instantly swung upon its pivot so as to project the 5 spout B through the slot 15 in order that oil may be discharged. This operation can be performed by one hand or in other words, by the hand that holds the wrench. In addition to this it provides a definite place for storing 10 the oil can so that loss of the same is impossible, and it is also protected from damage by the handle.

While this handle may be found especially useful in connection with wrenches, it may 15 be used in connection with all forms of tools requiring handles.

What is claimed is:—

1. A device of the character described comprising a body member having a chamber therein, said body member having an 20 opening in one of its sides and a slot in the opposite side communicating with said chamber, and an oil can pivoted in said chamber, the body of said can being movable through the opening of the chamber, the spout of the can being movable through 25

the slot upon pivotal movement of the can within the chamber.

2. Means for supporting an oil can comprising a sheet of material bent upon itself 30 to provide a U-shaped housing, the intermediate portion of said housing having a slot, a shaft mounted in said housing, an oil can, a collar adjacent its base, said collar having a pair of projecting ears, said ears being 35 freely mounted on said shaft, the spout of said oil can being movable through the slot upon pivotal movement of the can.

3. Means for supporting an oil can comprising, a hollow body member open at its 40 ends and one side, the opposite side of said body member having a slot, one of said ends being secured to the ends of the shank, a spring clip extending over the other end of the body member, and an oil can mounted in 45 said body member for oscillating movement, said can being retained in the body member by the clip and movable simultaneously through said open side and slot.

In testimony whereof I hereunto affix my 50 signature.

CLINT W. RIEFF.
